UNITED STATES PATENT OFFICE.

HARRIET M. JOHNSTON, OF MUNCIE, INDIANA.

DESIGN FOR A HOLDER FOR FOUNTAIN-PENS AND FILLERS.

SPECIFICATION forming part of Design No. 26,580, dated February 2, 1897.

Application filed November 5, 1895. Serial No. 611,183. Term of patent 21 years.

To all whom it may concern:

Be it known that I, HARRIET M. JOHNSTON, a citizen of the United States, residing at Muncie, in the county of Delaware and State of Indiana, have invented and produced a new and original Design for Fountain-Pen and Filler Holders; and I do hereby declare the following to be a full, clear, and exact description of the same, reference being had to the accompanying drawings, forming a part thereof.

This design relates to a fountain-pen and filler holder, designed to be worn by stenographers, &c., and is illustrated in the accompanying drawings.

Figure 1 is a front elevation of a holder, showing my design. Fig. 2 is a rear elevation; and Fig. 3 is a sectional elevation taken at a point indicated by lines *x-x*, Fig. 3, these drawings being deemed necessary to fully illustrate my design.

The leading feature of my design consists in the combination of a central field having radiating therefrom streamers or ribbons in representation of a bow or rosette, of two depending flaps or ribbons in parallel relation to each other, each of a different length, each ribbon extending upwardly from its lower portion and then downwardly upon itself for a short distance, each in different vertical

planes, the short downwardly-extending portions being provided with a pattern, as shown, the extreme lower ends being fringed. 30

1 designates the central field, having radiating therefrom streamers or ribbons 2, which blend into the central field, the whole being 35 in representation of a bow or rosette. Depending from the central field are two ribbons 3 and 4, of different lengths. Each ribbon is bent upon itself at 5, forming pockets, the ends being bent downward at 5' and secured 40 to the body of the ribbon by ornamented stitches 6. The extreme ends of the ribbons are fringed, as shown at 7, whereby the depending ribbons present a neat and attractive appearance. The holder as thus constructed 45 and arranged presents a neat and attractive appearance, and when attached to the dress of a person blends with the wearing-apparel to subserve the purpose of an ornament.

What I claim is— 50

The design for a fountain-pen and filler holder, substantially as shown and described.

In testimony whereof I affix my signature in presence of two witnesses.

HARRIET M. JOHNSTON.
